UNITED STATES PATENT OFFICE

162,315

CIGAR LIGHTER

Julius Kohn, New York, N. Y.

Application October 12, 1950, Serial No. 12,539

Term of patent 14 years

(Cl. D48—27)

To all whom it may concern:

Be it known that I, Julius Kohn, a citizen of the United States, residing in New York city, in the county of New York, and State of New York, have invented a new, original, and ornamental Design for a Cigar Lighter, of which the following is a specification, reference being had to the accompanying drawing, forming a part hereof.

In the drawing:

The dotted lines shown in the drawing are for illustrative purposes only.

I claim:

The ornamental design for a cigar lighter, as shown and described.

JULIUS KOHN.
